RECOVERY OF DISTILLATE HYDRO-CARBONS FROM WELL FLUIDS

Earl S. Hill, Tulsa, Okla., assignor to Stanolind
Oil & Gas Company, Tulsa, Okla., a corpora-
tion of Delaware

Application August 31, 1939, Serial No. 292,818

7 Claims. (Cl. 196—8)

This invention relates to the recovery of "distillate" hydrocarbons from well fluids containing the same. More particularly it relates to improved processes for recovering such distillate hydrocarbons at high pressures whereby the residual gas can be injected into an underground reservoir with a minimum of compression.

Naturally-occurring reservoirs have been discovered in recent years in which both normally gaseous and normally liquid hydrocarbons exist, principally in a uniformly distributed condition usually referred to as a gas phase. In producing from such reservoirs it has been found that reducing the pressure of the well fluids causes the separation of a relatively small amount of a volatile liquid hydrocarbon fraction from the residual gas which can be recovered by means of a trap or separator. This liquid fraction is called "distillate" and the wells producing from such reservoirs are now classified as distillate wells.

The reservoirs from which distillates are produced are invariably at high pressures and temperatures, for example 2000 to 4000 or more pounds per square inch and 125° to 225° F. or higher, and the distillate well fluids almost always contain a great preponderance of the lighter hydrocarbons, the methane content thereof being generally above 80% and usually in the vicinity of 90% by volume. The content of butanes and heavier hydrocarbons is small and consequently these hydrocarbons are difficult to recover in satisfactory yields.

It is well understood that the condensation of distillate upon reducing the pressure of the well fluid is due to the phenomenon known as retrograde condensation which occurs at relatively high pressures and between the critical temperature of the hydrocarbon mixture under consideration and the maximum dew point of that mixture. At each temperature within these limits there is a pressure at which the maximum yield of distillate can be separated from a well fluid containing the same and this maximum yield increases with decreasing temperature. The usual method of recovering distillate from such a well fluid is by reducing its pressure, for example by expansion through a valve with or without auxiliary cooling to a desired pressure, for example 700 to 1200 pounds per square inch and then separating the condensed liquid from the residual gas. Generally sufficient cooling is employed so that the separation is carried out at a temperature below +50° F., for example at 0° to +40° F.

The effect of producing from distillate-contain-

ing reservoirs upon the material remaining therein is extremely important. If the reservoir pressure is allowed to decrease during production more and more of the valuable normally liquid hydrocarbons therein will be precipitated by virtue of the retrograde condensation phenomenon and thus will not be produced with the well fluid. It is therefore desirable to recycle the residual gas after the recovery of distillate therefrom to the producing formation in order to maintain its pressure and avoid loss of distillate as explained above. Recycling in this manner, however, involves the recompression of large volumes of residual gas to pressures in excess of well head pressures and the cost of such compression is very high, especially if the separation of distillate is carried out at a relatively low pressure.

From the above it will be understood that the customary method of distillate recovery with recycling has a considerable number of disadvantages among which are limited yield of distillate, high cooling costs and high compression costs. Another disadvantage incident to the use of low separator temperatures is the danger of natural gas hydrate formation in the apparatus due to the small amount of moisture present in substantially all distillate well fluids.

I have found that all of the above disadvantages can be substantially completely eliminated by changing the composition of the well fluid being processed by contacting the same with a relatively non-volatile liquid miscible with the distillate in an amount sufficient to increase the critical temperature of the resulting system to ordinary atmospheric temperature or above and separating the liquid material from the residual gas at a temperature below that critical temperature. Since the separation step according to my method is carried out on a mixture below its critical temperature the retrograde condensation phenomenon is not involved but the normal sequence of condensation and vaporization occurs. Also the temperature-pressure-yield relationship is changed in such a way that improved distillate yields are obtained at pressures much higher than can be economically used in processing the well fluid alone, thus greatly reducing the compression costs incident to recycling operation. Obviously separation at atmospheric temperature or above either eliminates the gas hydrate problem or allows the use of simple and inexpensive types of water removal.

In distillate recovery processes of the type last mentioned, I have found further that efficiency is increased and costs lowered by carrying out

the contacting operation at a pressure above 1500 pounds per square inch and preferably at a pressure in the range from about 2000 to about 4000 pounds per square inch and heating the separated liquid fraction at substantially the same pressure to remove a portion of the normally gaseous constituents therefrom prior to reduction of pressure to produce the desired distillate hydrocarbons. The heating step gives in effect a partial stripping action which materially increases the proportion of fixed hydrocarbon gases released at high pressure for recompression rather than at a lower pressure which would, of course, require additional compressor capacity. Another feature of great practical importance is based upon the fact that most distillates contain a small percentage of material boiling above the usual boiling range of gasoline. This relatively heavy material is particularly suitable for introduction into the contacting stage and its use in that manner eliminates the cost involved in providing an extraneous relatively non-volatile contacting medium. These and other features will be hereinafter described more fully.

It is an object of my invention to provide a novel and efficient process for recovering distillate hydrocarbons from well fluids containing the same. Another object is to provide an improved process for recovering increased yields of distillate while eliminating the residual gas from the system at high pressure whereby the cost of recycling the same to the producing formation is minimized. A further object is to provide a distillate recovery method which will economically separate and produce a high ratio of high pressure residual gas to low pressure gas. Further objects and advantages of my invention will be apparent from the following detailed description thereof read in conjunction with the drawings, in which:

Figure 1 represents in diagrammatic form a preferred distillate recovery plant according to my invention, and

Figure 2 represents a second form of apparatus according to my invention, also in diagrammatic form.

In one of its broad aspects my invention comprises contacting a distillate well fluid at a high pressure in excess of 1500 pounds per square inch with a relatively non-volatile liquid medium miscible with the distillate hydrocarbons, separating residual gas from the resulting liquid phase and heating the latter without substantial pressure reduction to drive off an additional quantity of undesirably light gases. Preferably the pressure in the contacting step is maintained in the range from about 2000 to about 4000 pounds per square inch, for example 2500 pounds per square inch, and the temperature in the range from about 75° F. to about 125° F., suitably about 100° F. While any convenient contacting method can be employed this operation is best carried out countercurrently in a bubble plate tower or the like and the heating step performed in the lower portion thereof. In any case it is desirable that the gases evolved in the heating step be returned to the contacting zone to prevent undue loss of the butanes and heavier hydrocarbons present therein. The high pressure residual gas is preferably compressed for injection into the producing formation. Under some conditions it may be desirable to compress the well fluid prior to treatment in accordance with my invention and inject the residual gas directly into an input well

and this can be done without departing from my invention.

As the relatively non-volatile liquid introduced into the contacting step I can use any liquid material less volatile than the distillate to be recovered and miscible therewith. This can be, for example, an absorption oil or gas oil from an extraneous source, but preferably is a heavy distillate fraction separated from the desirable portions thereof by fractionation. Thus when motor gasoline is being produced the relatively heavy fraction will have an initial boiling point in the neighborhood of 400° F. whereas the initial boiling point can be as low as 260° F.-300° F. when natural gasoline meeting market specifications is the desired product. In any case the relatively heavy oil is introduced into the contacting zone in sufficient quantity to increase the critical temperature of the hydrocarbon system above the temperature at which the residual gas is withdrawn from the contacting step, but usually a somewhat greater amount, for example, about 2 to 6 gallons per thousand cubic feet are employed in order to obtain still greater yields.

As stated above a small quantity of water generally accompanies distillate well fluids and this is preferably removed in order to avoid emulsion difficulties in the contacting step and under some conditions to avoid natural gas hydrate formation. A simple and effective method of doing this is to introduce the well fluid at well head pressure with or without some preliminary cooling into a separator and remove the liquid water from the lower portion thereof. Generally speaking, a certain proportion of the distillate hydrocarbons are in the liquid phase at the well head because of the pressure drop occurring in the tubing and this also collects in the water separator as an upper layer, which can be withdrawn from the system or introduced into the contacting zone or into a subsequent fractionating zone if desired.

Further details of my invention can best be understood from the description of the apparatus shown in the drawings and the manner in which they operate in accordance therewith.

Referring now to Figure 1 a producing well 10 is shown which is of the distillate type as hereinbefore defined. The well fluid flowing therefrom at the well head will be at a relatively high pressure and temperature, for example about 1500 to 4000 or more pounds per square inch and about 75° F. to 225° F. depending primarily upon the bottom hole temperature and pressure, the composition and the rate of production. This fluid passes through valve 11 and line 12 and either through valve 13 or through valve 14, cooler 15 and valve 16 to separator 17. Normally these valves are manipulated so that there is no substantial pressure reduction between the well 10 and separator 17. In order to remove as much water from the well fluid as possible sufficient cooling is preferably supplied by cooler 15 so that the temperature maintained in separator 17 is above the temperature at which natural gas hydrates form at the pressure existing therein. The liquid water separates out as a lower layer and is withdrawn from the system through line 18 controlled by liquid level control 19. As stated above a portion of the distillate hydrocarbons also separates from the well fluid and this forms an upper layer, which is withdrawn from separator 17 through line 20 controlled by liquid level control 21. The material in line

20 can be either removed from the system through valve 22 and line 23 or introduced into other parts thereof through line 24 as will be described below.

The well fluid, which now has a substantially reduced water content, is removed from the upper portion of separator 17 and passes by means of line 25 through pressure control 26 into contacting tower 27 at an intermediate point therein. Pressure control 26 is arranged so that it is responsive to the pressure within tower 27 and is designed to cause little or no pressure drop when the system is operating in a stable fashion, but prevents sudden fluctuations in tower pressure if the rate of production varies. The liquid material from separator 17 in line 24 can also be introduced into tower 27 by opening valve 28 and this is the preferred method of operation since this liquid contains a large proportion of hydrocarbons lighter than butane. As shown, tower 27 consists of two sections both of which are equipped with bubble plate trays or similar devices for insuring intimate contact between gas and liquid phases. The upper section 29 is the contacting section through which the well fluid flows upward and is countercurrently contacted with a cool liquid medium which is less volatile than the distillate to be recovered and miscible therewith supplied through line 30 under control of valve 31. As stated above the liquid medium is introduced into the upper portion of contacting section 29 in an amount sufficient to raise the critical temperature of the entire composition in section 29 above the temperature existing therein. The well fluid in flowing up contacting section 29 gradually loses its content of distillate hydrocarbons and the residual gas is withdrawn through line 32, recompressed by compressor 33 to a pressure sufficient to allow its injection into the producing formation and thence through line 34 and valve 35 to input well 36. Line 32 is equipped with a pressure control device 37 so that the pressure within tower 27 is maintained at a desired value in excess of 1500 pounds per square inch and preferably in the range from about 2000 pounds per square inch to about 4000 pounds per square inch.

Lower section 38 of tower 27 is a stripping section through which the liquid from the bottom of contacting section 29 descends. Heat is supplied to the lower portion of stripping section 38 by means of reboiler 39 thus producing a gas phase which flows upward through stripping section 38 in contact with the descending liquid, the fixed gases continuing to ascend through contacting section 29. By this arrangement the liquid in the bottom of tower 27, which is a mixture of the relatively heavy medium supplied through line 30 and the desired distillate hydrocarbons is kept relatively free from fixed gases such as methane and ethane which would otherwise have to be withdrawn from the system at a lower pressure. The gases stripped from the liquid in stripping section 38 may amount in some cases to as much as 5% of the total residual gas so that it is apparent that compression costs of substantial magnitude are eliminated by operation according to the procedure above described as compared with releasing an equivalent amount of undesirable light gas at a lower pressure.

The composite liquid in the lower portion of tower 27 is removed therefrom under control of liquid level control 40 through line 41 and cooler 42 to the lower portion of flash tower 43. Tower 43 is maintained at a substantially lower pressure than tower 27 and this pressure can suitably lie

in the range from about 700 to about 1200 pounds per square inch. Due to the reduction in pressure in tower 43 additional quantities of light hydrocarbons are vaporized and these pass upwardly and are contacted with a descending stream of relatively heavy liquid supplied to the upper portion thereof through line 44 and valve 45. The liquid thus supplied can suitably be of the same type supplied to tower 27 and its purpose is to prevent undue loss of valuable butanes and heavier hydrocarbons. The remaining vapors are withdrawn from the top of tower 43 through line 46, pressure control 47 and line 48 and are compressed by compressor 49 for introduction into line 32 and ultimate reinjection into input well 36. Obviously, of course, this stream can be withdrawn from the system for use as fuel or otherwise, or after compression can be reintroduced into tower 27.

The liquid collecting in the bottom of tower 43 flows through liquid level controlled valve 50 and line 51 into stabilizer 52 which is maintained at a still lower pressure, for example 200 to 400 pounds per square inch. Stabilizer 52 can be of conventional design and as shown has a heating coil 53 in the lower portion thereof to supply the necessary heat and a cooling coil 54 in the upper portion thereof to supply the reflux necessary for efficient stabilization. The overhead is withdrawn through line 55 and pressure control 56 for use as fuel or other desired purpose, while the stabilized liquid passes through liquid level controlled valve 57 and line 58 into fractionator 59, which is operated at a pressure which may range from about atmospheric to about 50 pounds per square inch.

Fractionator 59 can also be of conventional design and as shown heat is supplied to the lower portion thereof by means of coil 60 and the overhead passes through line 61 and condenser 62 to drum 63 in which the desired liquid product is separated from uncondensed gas. This gas is removed from the system through line 64 while the product flows through line 65 to storage. A portion of the product in line 65 is introduced into the upper portion of fractionator 59 as reflux by means of pump 66 and line 67. Obviously fractionator 59 can be operated to produce an overhead product having any desired end point, for example gasoline of an end point of 375° to 400° F. or natural gasoline having an end point below 300° F. can be obtained.

All of the material not taken overhead is withdrawn from the bottom of fractionator 59 through level controlled valve 68 and line 69 and this will include substantially all of the liquid introduced into towers 27 and 43 through lines 30 and 44 respectively together with that portion of the distillate which boils above the boiling range of the desired product. In my preferred method of operation most of this relatively heavy liquid in line 69 passes through valve 70, line 71, cooler 72, line 73 and pumps 74 and 75 into lines 30 and 44 for introduction into towers 27 and 43 respectively, while the excess is withdrawn from the system through valve 76 as a heavy product. In starting operation it will be necessary to introduce an extraneous non-volatile liquid such as absorption oil and this can be done through line 77 and valve 78.

It is apparent from the above that I have described a simple and efficient method of recovering distillate from high pressure well fluids containing the same. Under certain conditions it may be desirable to modify the system described

and one skilled in the art would have no difficulty in arranging apparatus of somewhat different types in order to accomplish equivalent results, for example instead of introducing the extremely volatile liquid in line 24 into tower 27 it can be passed to tower 43 by closing valve 28 and opening valve 79 in line 80. Certain other modifications are illustrated in Figure 2 to which reference is now made.

In many respects the distillate recovery plant illustrated in Figure 2 is the same as that shown in Figure 1 and the operation of the various parts thereof is similar except as otherwise hereinafter stated. Distillate-containing well fluid from producing well 90 which has been cooled if desired in cooler 91 is introduced into separator 92 in which the liquid water and liquid hydrocarbons separate from the gaseous material. Water is withdrawn from the system through line 93 while the liquid hydrocarbons and gaseous hydrocarbons are both introduced into contact tower 94 by means of lines 95 and 96 respectively. Tower 94 differs from tower 27 of Figure 1 in that it contains a single section of bubble trays or the like and the fluid streams from separator 92 are introduced into the lower portion thereof. Relatively heavy liquid material is supplied to the upper portion of tower 94 through valve 97 and line 98 so that the gaseous portion of the well fluid is counter-currently contacted therewith. The residual gas flows through line 99, pressure control 100, line 101, compressor 102, line 103 and valve 104 to input well 105, while the liquid collecting in the bottom of tower 94 flows through line 106 to partial stripper 107. The upper portion of stripper 107 is directly connected by line 108 with the lower portion of tower 94 above the liquid level so that tower 94 and stripper 107 are at substantially the same pressure. Heating coil 109 in the lower portion of stripper 107 supplies the heat necessary to vaporize a substantial portion of the methane and ethane in the liquid supplied thereto and this gaseous fraction passes through line 108 to be contacted with the heavy liquid from line 98 to prevent excessive loss of butanes and heavier hydrocarbons.

The partially stripped liquid flows through liquid level controlled valve 110, cooler 111 and valve 112 to separator 113 which is maintained at a substantially lower pressure, for example 700 to 1200 pounds per square inch. The vapors evolved at this pressure pass upward in contact with reflux due to cooling coil 114 in the upper portion of separator 113 and the fixed gases are withdrawn through line 115, pressure control 116, compressor 117 and line 118 to line 108 for further treatment in tower 94 and ultimate reinjection through input well 105. The remaining liquid collecting in the bottom of separator 113 passes through liquid level controlled valve 119 and line 120 thence through valve 121 to the top portion of fractionator 122 which is maintained at a relatively low pressure, for example about 50 pounds per square inch.

As an alternate procedure, the liquid in line 120 may be caused to pass through valve 123 into fractionator 122 at a point a few plates below the top plate, so that the reflux from the top plates will keep down the end-point of the finished gasoline from stabilizer 137.

Sufficient heat is supplied to the lower portion of fractionator 122 by means of heating coil 124 so that all of the desired distillate hydrocarbons are driven overhead through line 125 while the fraction heavier than the desired product flows

from the bottom thereof through level controlled valve 126, line 127 and either through valve 128 to storage or preferably for the most part through valve 129, line 130, cooler 131, line 132 and pump 133 to line 98 for reintroduction into contact tower 94. As in Figure 1 an extraneous heavy oil can be introduced into the system by means of line 134 and valve 135.

The vapors in line 125 still contain a considerable quantity of hydrocarbons too light for use in either motor gasoline or natural gasoline and consequently they are passed by means of pump 136 directly into stabilizer 137 which operates in the usual manner, preferably at a pressure in the range from 200 to 400 pounds per square inch. Gasoline having the desired characteristics is taken off as bottoms through line 138 and cooler 139 while the overhead passes through pressure control valve 140 and cooler 141 to stabilizer reflux drum 142. Fixed gas passes from the system through line 143 while the volatile liquid in drum 142 is withdrawn through line 144 and a portion thereof is introduced into the top of stabilizer 137 as reflux through pump 145 and valve 146.

Many details which have been omitted in the above description have not been given in order that my invention can be more readily understood, such details, however, being easily supplied by those skilled in the art. Among them are the construction and operation of the apparatus according to my invention for any particular well fluid or fluids, the use of indirect heat exchange at various points in order to conserve heat, etc. Furthermore, it is obvious that the fluid from a plurality of distillate wells can be combined and the distillate recovered therefrom according to my invention in the same manner as hereinabove described for the fluid from a single well, and that a plurality of input wells can likewise be used.

While I have described my invention in connection with certain specific embodiments thereof, it is to be understood that these are by way of illustration and not by way of limitation, and that I do not mean to be bound thereby but only by the appended claims in which I have defined my invention.

I claim:

1. A method of recovering gasoline-range distillate hydrocarbons from a high pressure well fluid containing the same which comprises contacting said well fluid in a contacting zone with a liquid absorption medium having an initial boiling point of at least 260° F., said boiling point being sufficiently high to permit the recovery of said distillate hydrocarbons from said liquid absorption medium by distillation therefrom, said contacting being conducted at a pressure in excess of about 1500 pounds per square inch, separately removing residual gas and a liquid fraction including said liquid absorption medium and said distillate hydrocarbons from said contacting zone, introducing said liquid fraction into a separation zone maintained at a pressure within the range from about 700 to about 1200 pounds per square inch, removing the gases evolved in said separation zone from the upper portion thereof, removing a liquid fraction from the lower portion of said separation zone, and recovering said distillate hydrocarbons from said last mentioned liquid fraction by distillation therefrom.

2. The method of recovering distillate hydrocarbons from a high pressure well fluid containing the same which comprises contacting said

well fluid in a contacting zone with a liquid medium substantially less volatile than, and miscible with, the distillate to be recovered, at a pressure in excess of about 1500 pounds per square inch, separately removing residual gas and a liquid fraction including said liquid medium and said distillate hydrocarbons from said contacting zone, heating said liquid fraction under a pressure substantially the same as that in said contacting zone to produce a vapor fraction containing light gaseous hydrocarbons and a second liquid fraction therefrom, returning said vapor fraction to said contacting zone, introducing said second liquid fraction into a separation zone maintained at a pressure in the range from about 700 to about 1200 pounds per square inch, removing the gases evolved in said separation zone from the upper portion thereof, removing a third liquid fraction from the lower portion of said separation zone, and recovering distillate hydrocarbons from said third liquid fraction.

3. The method of claim 2 including the step of introducing another portion of said liquid medium into the upper portion of said separation zone to contact said gases evolved therein.

4. The method of claim 2 including the steps of compressing said gases from said separation zone and introducing said compressed gases into said contacting zone.

5. The method of recovering distillate hydrocarbons from a high pressure well fluid containing the same which comprises contacting said well fluid in a contacting zone with a liquid absorption medium substantially less volatile than and miscible with said distillate hydrocarbons, said liquid absorption medium having an initial boiling point sufficiently high to permit recovery of said distillate hydrocarbons from said liquid absorption medium by distillation, said contacting being conducted at a pressure in excess of about 1500 pounds per square inch, separately removing residual gas and a liquid fraction including said liquid absorption medium and said distillate hydrocarbons from said contacting zone, cooling said liquid fraction to a temperature lower than the temperature existing in said contacting zone, introducing said cooled liquid fraction into a separation zone maintained at a superatmospheric pressure substantially lower than the pressure of said contacting step, contacting gases evolved in said separation zone with another portion of liquid absorption medium and recovering distillate hydrocarbons from said last mentioned portion of said liquid absorption medium after contacting said gases and from the liquids remaining after the evolution of said last mentioned gases, and recycling said liquid absorption medium, from which said distillate hydrocarbons have been recovered, to said contacting zone and to said last mentioned contacting step.

6. The method of recovering distillate hydrocarbons from a high pressure well fluid containing the same which comprises contacting said

well fluid in a contacting zone with a liquid absorption medium substantially less volatile than and miscible with said distillate hydrocarbons, said liquid absorption medium having an initial boiling point sufficiently high to permit recovery of said distillate hydrocarbons from said liquid absorption medium by distillation, said contacting being conducted at a pressure in excess of about 1500 pounds per square inch, separately removing residual gas and a liquid fraction including said liquid absorption medium and said distillate hydrocarbons from said contacting zone, cooling said liquid fraction to a temperature lower than the temperature existing in said contacting zone, introducing said cooled liquid fraction into a separation zone maintained at a pressure within the range from about 700 to about 1200 pounds per square inch, contacting gases evolved in said separation zone with another portion of liquid absorption medium and recovering distillate hydrocarbons from said last mentioned portion of said liquid absorption medium after contacting said gases and from the liquids remaining after the evolution of said last mentioned gases, and recycling said liquid absorption medium, from which said distillate hydrocarbons have been recovered, to said contacting zone and to said last mentioned contacting step.

7. The method of recovering distillate hydrocarbons from a high pressure well fluid containing the same which comprises contacting said well fluid in a contacting zone with a liquid absorption medium substantially less volatile than and miscible with the distillate hydrocarbons to be recovered, said liquid absorption medium having an initial boiling point sufficiently high to permit recovery of said distillate hydrocarbons from said liquid absorption medium by distillation, said contacting being conducted at a pressure in excess of about 1500 pounds per square inch, separately removing residual gas and a liquid fraction including said liquid absorption medium and said distillate hydrocarbons from said contacting zone, introducing said liquid fraction into a zone the upper portion of which constitutes a second contacting zone and the lower portion of which constitutes a liquid-gas separation zone, contacting the gases evolved in said separation zone with a further quantity of said liquid absorption medium in said second contacting zone, removing residual gases from the upper portion of said second contacting zone, removing liquid hydrocarbons containing said liquid absorption medium and said distillate hydrocarbons from the lower portion of said separation zone, distilling said liquid hydrocarbons to separate said distillate hydrocarbons from said liquid absorption medium, and recycling at least a substantial part of said liquid absorption medium to said first mentioned contacting zone and to said second contacting zone.

EARL S. HILL.
